UNITED STATES PATENT OFFICE.

JACOB A. O'DELL, OF CLEVELAND, OHIO.

DESIGN FOR A DOOR-SECURER MEMBER.

SPECIFICATION forming part of Design No. 31,143, dated July 4, 1899.

Application filed May 28, 1898. Serial No. 682,069. Term of patent 7 years.

To all whom it may concern:

Be it known that I, JACOB A. O'DELL, a citizen of the United States, residing at Cleveland, in the county of Cuyahoga and State of Ohio, have invented and produced a new and useful Design for a Door-Securer Member, of which the following is a specification.

The leading feature of my design for a door-securer member consists in the peculiar shape 10 of the device as a whole, which will be fully described hereinafter.

In the drawing forming part of this specification the figure is a perspective view of the invention constructed according to my design.

Referring to the drawing by letter, A is the body portion of my door-securer member, which consists of a straight bar having par-

allel sides and edges curved, as at B, at one end and provided with an inclined serrated 20 end C at the remaining end. It will be noticed that each end has a thickened portion or shoulder P and E.

F is a perforation at the curved end of the body portion and extends transversely 25 through the same.

Having thus described my invention, what I claim as new, and desire to secure by Letters Patent, is—

The design for a door-securer member, substantially as herein shown and described.

JACOB A. O'DELL.
